United States Patent Office

Des. 182,161
Patented Feb. 25, 1958

182,161

ROLL PAPER HOLDER

Elvah O. Bulman, Grand Rapids, Mich., assignor to The
E. O. Bulman Manufacturing Company, Inc., Grand Rapids, Mich., a corporation of Michigan

Application February 13, 1956, Serial No. 40,120

Term of patent 7 years

(Cl. D4—3)

Fig. 1.

Fig. 2.

Fig. 1 is a perspective view of a roll paper holder, showing my new design.

Fig. 2 is an end view of the same.

The end not shown is the same as that illustrated in Fig. 2.

The broken line portion illustrating a roll of paper is for purpose of illustration only.

I claim:

The ornamental design for a roll paper holder, as shown and described.
